CLAIM

The ornamental design for a nested bowl assembly as shown and described.

DESCRIPTION

FIG. 1 is a top, front, right side perspective view of a nested bowl assembly showing the claimed design;

FIG. 2 is a front elevational view thereof, wherein the rear elevational view is the same and thus omitted;

FIG. 3 is a left side elevational view thereof, wherein the right elevational view is the same and thus omitted;

FIG. 4 is a top plan view thereof;

FIG. 5 is a bottom plan view thereof;

FIG. 6 is a bottom, rear, left side perspective view thereof;

FIG. 7 is a top, front, right side exploded perspective view thereof;

FIG. 8 is a front elevational exploded view thereof;

FIG. 9 is a bottom, rear, left side exploded perspective view thereof; and,

FIG. 10 is a top plan view of the nested bowl assembly shown with the two small upper bowls removed for ease of illustration.

The dashed broken lines in the drawings depict portions of the nested bowl assembly that form no part of the claimed design.

1 Claim, 10 Drawing Sheets
